Chris Myhre

UNITED STATES PATENT OFFICE.

CHRIS MYHRE, OF ST. LOUIS, MISSOURI, ASSIGNOR OF ONE-HALF TO JOHN P. BECKER, OF SAME PLACE.

PERMUTATION-PADLOCK.

SPECIFICATION forming part of Letters Patent No. 557,012, dated March 24, 1896.

Application filed May 21, 1895. Serial No. 550,148. (No model.)

To all whom it may concern:

Be it known that I, CHRIS MYHRE, of the city of St. Louis, State of Missouri, have invented certain new and useful Improvements 5 in Permutation-Padlocks, of which the following is a full, clear, and exact description, reference being had to the accompanying drawings, forming a part hereof.

My invention relates to an improved permutation-padlock; and it consists in the novel construction, combination, and arrangement of parts hereinafter described and claimed.

In the drawings, Figure I is a side elevation of my improved padlock. Fig. II is a vertical sectional view on the indicated line II II 15 of Fig. I. Fig. III is a top plan view of one of the fixed disks. Fig. IV is a top plan view of one of the rotating disks. Fig. V is a top plan view of my improved padlock, the shackle 20 or link thereof being removed. Fig. VI is a side elevation of the shackle or link. Fig. VII is a view in perspective of the body of the lock.

Referring by numerals to the accompanying drawings, 1 indicates the body or center-post of the device, the same being in the form of a vertically-arranged rod having a fixed base-plate 2. Extending the entire length of the center-post 1 is a rectangular groove 3, 30 that communicates with a recess 4 formed in the base-plate. At right angles to the groove 3 and extending the entire length of the post 1 is a triangular groove 5.

6 indicates a rectangular lug that is formed integral with the upper end of the post 1 and extends in alignment with and from the rear end of the vertical groove 3 to the opposite side of the post 1. In the face of said integral rectangular lug 6 toward the groove 3 is 40 formed a screw-threaded aperture 7.

Rotating disks 8, of the same diameter as is the base 2, are constructed with star-shaped apertures 9 in their centers. Leading from the outer points of these star-shaped apertures to the edges of said disks are indicating-lines 10, and upon the peripheries of each of said disks adjacent said indicating-lines is a series of letters or numerals 11. In each of the star-shaped apertures is removably located a star-shaped disk 12, in the center of which is a circular aperture 13, from which

extends into the body of the disk a rectangular notch 14.

Fixed disks 15 are of the same diameter as are the disks 8 and base 2, and said disks are 55 preferably thinner than are the disks 8. In the centers of said disks are formed circular apertures 16, which are of the same diameter as are the apertures 13 in the star-shaped disks 12. Extending into the bodies of the 60 disks 15 from the centrally-arranged apertures 16 are rectangular notches 17 of the same size as are the rectangular notches 14.

Formed integral with the bodies of the disks 15 and extending into the apertures 16 65 therein at points approximately at right angles to the notches 17 are triangular lugs 18 of such a size as to fit in the triangular groove 5 in the center-post 1. It is essential that the disks 8 and 15 be alternately held 70 one on top of the other and arranged upon the center-post 1. When the disks 15 are located upon said center-post the lugs 18 are slipped downwardly through the triangular groove 5 in said center-post.

19 indicates a cap or top plate for the padlock, the same being constructed with a transversely-extending rectangular slot 20 that communicates and is in alignment with a rectangular groove 21 formed in the top surface of said plate. On the opposite side of the top face of this plate 19 and in alignment with said slot 20 and groove 21 is a rectangular groove 22, and passing through the wall 23 that separates this groove 22 from the centrally-arranged rectangular slot 20 is an aperture 24. Formed in the under side of this top plate 19 is a circular recess 25^a which allows said plate to be located upon the top of the center-post 1, and after the disks have 90 been alternately and properly located upon said center-post and the top plate upon the last one of said disks and on the top of said center-post a screw 25 is passed through the horizontally-aligned apertures 23 and 7. This 95 very effectually holds the disks upon the center-post and prevents them from becoming accidentally removed.

26 indicates the shackle, the upper end of which is formed into a hook 27, and the body 100 of said shackle extends downwardly from the center of said hook and said body is attached

to one arm of said hook. Formed in the outer edge of the body of the shackle 26 is a series of rectangular notches 28 of such a width as that they will readily receive the thickness 5 of the star-shaped disks 12. The projecting lugs 29 between these notches 28 are of such thickness as that they will just fill the rectangular notches 17 in the disks 15. The lower one of these lugs 29 rests in the rectangular recess 4 formed in the base-plate 2. The end of the hook 27 to which the body of the shackle is fixed rests in the groove 21, while the top of the body of said shackle passes through the rectangular slot 20. The 15 end of the hook 27 that is not fixed to the body of the shackle 26 is adapted to be located in the rectangular groove or recess 22, and when so located it will be noted that the head of the screw 25 is entirely covered. When 20 the shackle is at its lowermost position and any or all of the disks 15 carrying the star-shaped disks 12 are rotated in either direction, said shackle will be very efficiently locked, as the rectangular notches 14 in the 25 star-shaped disks 12 are thrown out of alignment with the lugs 29 on the body 26 of said shackle.

It is essential that there be an indicating-mark on the exterior of the cap or top plate 30 19 in alignment with the rectangular notches 17 in the disks 15. This forms a guide for the operator in unlocking the padlock, and the disks 8 must be so turned as that the letters or numerals forming the set combination 35 are in vertical alignment with this indicating-mark.

Assuming that it is desired to set a combination the letters of which form the word "cow," the lowermost disk 8 and the star-shaped disk 12 carried thereby are so arranged 40 relative one another as that the rectangular notch 14 in said disk 12 is in direct alignment with the indicating-line 10 that leads to the letter "W" on the periphery of the disk 8. The next disk above this lowermost disk 12 and its star-shaped disk are so arranged relative one another as that the notch 14 in said 45 second star-shaped disk is directly opposite the indicating-line that leads to the letter "O" on the periphery of said second disk.

The top one of the disks 8 and the star-shaped disk 12 carried thereby are so arranged relative one another as that the rectangular notch 14 will come directly opposite the indicating-line that leads to the letter "C" on the periphery of said upper disk. When said 55 combination is so set and the disks are properly positioned upon the center-post and the shackle properly arranged within said post 60 and disks, the operator so rotates the disks 8

as that the letters "C, O, W" come in direct alignment with the indicating-mark upon the top of the cap 19. This necessarily brings all of the rectangular notches 14 into direct alignment with the notches 17, and when this is 65 done the padlock is unlocked and the shackle is free to be moved in and out of the center-post and disks.

The object of having a number of letters or indicating-marks upon the peripheries of 70 the revolving disks is to mislead any person trying to open the padlock when the combination is off, and also to enable the owner of the padlock to make a number of changes in the combination, this being done by arranging the star-shaped disks 12 relative the 75 disks 8.

When a padlock of my improved construction is locked and in use, the screw 25 that holds the various parts is entirely covered, 80 and said padlock can therefore in no wise be taken apart while the same is locked, this being the case in many padlocks where certain of the screws or rivets that hold the same together are exposed.

A padlock of my improved construction possesses superior advantages in point of simplicity, durability, and general efficiency, and is proof against the tamperings of unauthorized persons with a view to taking said padlock apart while the same is locked and in use.

I claim—

The improved permutation-padlock, comprising the base 2, the center-post 1, the series of disks mounted upon the said center-post, a rectangular lug 6 formed upon the upper end of said post and provided with a horizontal screw-threaded aperture 7, the cap 19 having the central slot 20 and provided with the rectangular slot 22 in alignment with said 95 slot 20 but located at one edge of said cap, there being a horizontal aperture 24 formed in the wall of said cap that separates said slot 22 from the slot 20, a screw 25 located in the said horizontal slots 22 and 24 and locking together 100 the said cap and said center-post, the head of said screw being located within the said slot 22, and the shackle 26 engaging said center-post and said disks and having the hook 27 at its upper end engaging in the said slot 22 and 105 covering the head of said screw, whereby the withdrawal of the latter is prevented until after the said shackle is withdrawn, substantially as herein specified.

In testimony whereof I affix my signature 115 in presence of two witnesses.

CHRIS MYHRE.
